[57] CLAIM

The ornamental design for a stand alone LED display, as shown and described.

DESCRIPTION

FIG. 1 is an environmental perspective view of a stand alone LED display showing my new design;

FIG. 2 is a front elevational view thereof;

FIG. 3 is a rear elevational view thereof;

FIG. 4 is a right side elevational view with the left side being a mirror image thereof;

FIG. 5 is a top view thereof; and,

FIG. 6 is a bottom view thereof.

The broken line showing of indicia in FIG. 1 and the power cord in FIGS. 1 and 3 is for illustrative purposes only and forms no part of the claimed design.
